(57) **CLAIM**

The ornamental design for a headset, as shown and described.

DESCRIPTION

FIG. 1 is a front, left perspective view of a headset in accordance with the present invention.

FIG. 2 is a front, right perspective view of the headset of FIG. 1.

FIG. 3 is a front elevation view of the headset of FIG. 1.

FIG. 4 is a rear elevation view of the headset of FIG. 1.

FIG. 5 is a left elevation view of the headset of FIG. 1.

FIG. 6 is a right elevation view of the headset of FIG. 1.

FIG. 7 is a top plan view of the headset of FIG. 1; and,

FIG. 8 is a bottom plan view of the headset of FIG. 1.

The broken lines in the drawings depict portions of the headset that form no part of the claimed design.

1 Claim, 8 Drawing Sheets
